UNITED STATES PATENT OFFICE

BENNETT M. LEECE, OF CLEVELAND, OHIO, ASSIGNOR TO THE LEECE-NEVILLE COMPANY, OF CLEVELAND, OHIO, A CORPORATION OF OHIO

REGULATOR

Application filed February 20, 1928. Serial No. 255,585.

This invention relates to regulators for dynamo electric machines particularly adapted for use in connection with generators which are operated under widely different conditions of speed and load, such, for example, as lighting and battery charging generators of automobiles and other engine driven vehicles. More particularly, the invention relates to a combined voltage and current regulator and in certain of its aspects is an improvement over Patent No. 1,874,856, dated April 12, 1921, and granted in the names of H. C. Branch and myself.

The chief object of the present invention is to provide a regulator which regulates the output of the machine both for voltage and current, maintaining the voltage substantially constant under widely different conditions of speed and load, and which controls the current output so that the generator will have a desirable current characteristic, the present regulator in so far as the current regulation is concerned becoming effective when the load reaches a predetermined amount. In this respect, the regulator is an improvement over that which constitutes the subject matter of the patent referred to.

In the accompanying sheets of drawings, Fig. 1 is a front view of a regulator embodying my invention, the same being in this instance combined with the usual reverse current cut-out; Fig. 2 is a side view of the same; Fig. 3 is a sectional view substantially along the line 3-3 of Fig. 1; Fig. 4 is a view similar to Fig. 1 showing a modification which for reasons to be explained is preferred to that shown in Fig. 1; and Fig. 5 is a diagrammatic view showing the circuit connections.

The regulator herein illustrated includes a base 10 of a suitable insulating material, which base may be applied to a suitable part of the automobile or other vehicle, assuming that it is used in connection with an engine driven vehicle. At the top of the base is attached the usual reverse current cut-out consisting of current and voltage coils which are superposed and designated in Fig. 1 by the reference character 11 and

which are shown diagrammatically in Fig. 5, wherein the current coil is designated 11^a and the voltage coil 11^b. The coils surround a core carried by a frame 12 having a pivoted armature 13 provided with a contact which cooperates with a stationary contact. As this cut-out embodies the usual parts or features, and as it functions in the usual way, it need not be further described.

The regulator, in so far as the voltage regulation is concerned, may have a single voltage coil which will respond to slight changes in voltage to effect the voltage regulation but preferably it is provided with two voltage coils arranged and functioning substantially as illustrated and described in my prior Patents No. 1,540,698, granted June 2, 1925, and No. 1,633,671, granted June 28, 1927. These two coils are superposed on a core attached to a frame 14 secured to the base 10 and are designated generally by the reference character 15 in Figs. 1 and 2, but in the diagrammatic view of Fig. 5 they are designated respectively 15^a and 15^b. The frame 14 carries a vibrating armature 16 having a contact 17 which is adapted to engage a stationary contact 18, the armature being biased toward closed position by an adjustable coil spring 19. It will be observed that the armature 16 which is pivoted to the frame 14 by means of a pintle 20 is provided with an enlarged extension 21 projecting outwardly beyond the magnet frame 14, this extension as well as the armature proper, the frame 14, and the core which is surrounded by the coils 15^a and 15^b being formed of magnetic material.

My improved regulator includes also a series coil 22 which in the construction illustrated in Figs. 1, 2 and 3 is supported by a frame 23 attached to the base 10. This frame, as clearly illustrated in Figs. 1, 2 and 3, includes a core 24 which the series coil surrounds, which core is secured to outstanding legs of the frame 23 and may be adjusted in an endwise direction or axially of the coil 22. This core has at one end a lateral extension 24^a which lies alongside or overlaps the enlargement 21 of the armature 16. The core 24 is formed of magnetic material but

the frame 23 is formed of non-magnetic material so that in effect the series coil has no closed magnetic path, for it is desirable that this series magnet have considerable leakage.

5 As before stated, the extension 24* of the core of the series magnet overlaps the extension 21 of the armature 16 but these overlapping members do not at any time actually engage each other. The gap between these parts may be adjusted by shifting the core 24 axially of the coil by first loosening the 10 screws 25 by which the core is supported on the legs of the non-magnetic frame 23, these screws passing through elongated slots in the 15 core.

It will be observed that magnetic flux threading between the extension 24* of the core 24 and the extension 21 of the armature 16 will exert a pull on the armature against the pull of spring 19, and, accordingly, this 20 magnetic pull has the effect of decreasing the strength of spring 19 and thus tends to separate the contacts of the vibrator. The arrangement and construction illustrated in 25 Figs. 1 to 3 are such that because of the lack of a closed magnetic path for coil 22, the series coil does not assist the voltage coil or coils to reduce the magnetic field of the generator until the load reaches substantially a 30 predetermined value, and at or about the time this load value is reached the series coil does become effective by its action on the armature 16 of the vibrator to control the voltage and therefore the current output.

35 A quite similar but slightly more effective arrangement is illustrated in Fig. 4 to which reference will now be had before describing the circuits. In Fig. 4 the vibrator and the reverse current cut-out are the same as in Figs. 1 and 2, and these parts need not be 40 again described, the same reference characters which are applied to Figs. 1 and 2 serving for the corresponding parts of Fig. 4. The regulator illustrated in Fig. 4 differs 45 simply in the arrangement of the series magnet and the way it cooperates with the vibrator to affect the voltage and, therefore, current output of the generator. In this instance the series coil 22 surrounds a core 26 50 supported by a frame 27 of magnetic material. This series magnet has a pivoted armature 28 to which is connected a spring 29 which holds the armature away from the core against a stop 30 which the core normally 55 engages. This armature has an extension 31 which overlaps the extension 21 of the vibrator armature 16 and is adapted to engage the face of the extension 21 on the side toward the spring 19. The arrangement 60 with this construction is such that the armature 28 is ineffective in so far as having any regulating function is concerned until the load exceeds a predetermined value, at 65 which time the armature 28 is attracted away from its seat 30 toward the core 26, and when

this occurs the extension 31 of the armature 28 will exert a pressure on the extension 21 of the vibrator armature, which pressure varies with the load in excess of the predetermined value and is against the pull of 70 spring 19.

75 It will be observed, therefore, that with the construction shown in Fig. 1 the magnetic pull exerted by the series coil weakens the spring 19, the extent depending upon the load after substantially the predetermined load value is reached, whereas with the construction illustrated in Fig. 4 the armature of the series magnet acts mechanically on the vibrator armature against the vibrator 80 spring 19, and here again the pressure exerted by the armature of the series magnet is proportional to the load after the load reaches a predetermined value. In both instances the series coil, when the predetermined load value has been reached, acts on the vibrator armature in a direction such as to tend to separate the vibrator contacts, thus assisting the voltage coil or coils in 85 their tendency to separate the vibrator contacts.

90 The circuit connections of the devices shown in Figs. 1 and 4 are precisely the same, and in Fig. 5 I have illustrated the arrangement shown in Fig. 4 as it has 95 proved to be somewhat preferable to that shown in Fig. 1 since the load value at which the series coil takes effect is more definite and more certain with the arrangement shown in Fig. 4 than with that shown in 100 Fig. 1.

95 In Fig. 5 the regulator is shown connected to a generator 32 having positive and negative brushes 33 and 34. In this instance a shunt generator is shown, having a field 105 winding 35. The load is illustrated as consisting of lamps 36 and a storage battery 37. It will be observed that the positive brush 33 of the generator is connected to a terminal 38 which in turn is connected by a conductor 39 to one terminal of the series coil 22 of the regulator, the other terminal of this coil being connected by a conductor 40 to a terminal 41 leading to one side of the load. The other load terminal 42 is connected by a conductor 43 to the stationary 110 contact 13* of the reverse current cut-out, the armature 13 of the cut-out being electrically connected to the cut-out frame 12, to which is connected one end of the series coil 115 120 125 130 135 140 145 150 155 160 165 170 175 180 185 190 195 200 205 210 215 220 225 230 235 240 245 250 255 260 265 270 275 280 285 the positive brush 33 of the generator. At this point it might be stated that when the vibrator contacts are open the resistance 48 is in series with the field winding 35 but when the contacts are closed the resistance is short circuited.

5 The voltage coil 11^b of the cut-out has one terminal connected to conductor 49 and its other terminal connected to conductor 44, and therefore this is connected directly across the terminals or brushes of the generator.

10 The vibrator is preferably provided with two voltage coils as previously explained, these being designated 15^a and 15^b. The coil 15^a may be termed the primary coil, this coil corresponding to the coil 21 of my Patent No. 1,540,698, or to coil 18 of my Patent No. 1,633,671, this coil having its circuit unaffected by the contacts of the vibrator. One end of this coil 15^a is connected to the vibrator frame 14 which is connected by a conductor 50 to conductor 39 leading to the positive brush of the generator. The other 15 end of this coil is connected by a conductor 51 to a resistance 52, which is preferably though not necessarily employed, this resistance being connected by a conductor 53 to the cut-out frame 12 and therefore to conductor 44 leading to the negative terminal or brush of the generator.

15 One end of the vibrator coil 15^b is connected by a conductor 54 to a conductor 55 which is connected to conductor 47 leading to one end of the field winding 35 and is also connected by a conductor 56 leading to the stationary contact 18. These contacts may be and preferably are bridged by a condenser 57. The other end of the vibrator coil 15^b is connected by a conductor 58 to the conductor 53 and to the resistance 52. This coil 15^b corresponds to the coil 22 of my Patent No. 1,540,698, and to coil 19 of my Patent No. 1,633,671. When the contacts are closed this coil 15^b is connected across the brushes of the generator in parallel with the field winding, and when the contacts are open it is in series with the field winding 35. To trace the circuits under both conditions, it might be stated that when the contacts are closed the circuit of the coil 15^b is as follows: From the positive brush 33, conductor 39, field frame 14, vibrator contacts, conductors 56 and 54 to the one end of coil 15^b, and from the other end of this coil by way of conductor 58 to conductor 53 to field frame 12 of the cut-out to series coil 11^a of the cut-out to conductor 44 and hence to the negative brush of the generator. 20 When the contacts are open, the circuit may readily be traced as follows: From the positive brush of the generator by conductors 39 and 50 to vibrator coil 15^a, through this coil and by conductor 51 to resistance 52 and 25 from this resistance by way of conductor 58

through coil 15^b and by conductors 54, 55 and 47 to one end of field winding 35 and through the field winding to the negative brush 34.

30 In other words, the connections are as in my patents above referred to. Therefore, as in my prior patents the coil 15^b causes the armature to vibrate by the rapidly interrupted or varying current passing through coil 15^b but its rate of vibration is determined principally by the current passing through the coil 15^a and therefore by the voltage of the generator impressed on this coil. That is to say, the voltage impressed upon the coil 15^a determines the rate of vibration of the vibrator armature until the load exceeds the predetermined value at which time the series coil becomes effective to increase the rate of vibrations by weakening the spring connected to the vibrator armature and thus protecting the generator from over-load and giving a current characteristic such as is desired for the best working conditions.

35 Having thus described my invention, I claim:

40 1. The combination with a dynamo electric machine having a field winding, of a regulator for varying the ampere turns of the field winding, said regulator having a vibratory armature, one or more voltage coils responsive to changes of voltage for 45 vibrating the same, and a series coil for affecting the rate of vibration when the load reaches a predetermined value, the voltage coil or coils and the series coil having separate magnetic paths.

45 2. The combination with a dynamo electric machine having a field winding, of a regulator for varying the ampere turns of the field winding, said regulator comprising a vibratory armature, one or more voltage coils for vibrating the same, and a series coil for exerting a force on the armature when the load reaches a predetermined value, the series coil being mounted on a core separate from that on which the voltage coil or coils 50 are mounted.

55 3. The combination with a dynamo electric machine having a field winding, of a regulator for varying the ampere turns of the field winding, said regulator having one or more voltage coils, a vibratory armature responsive to changes of voltage, a spring opposing the movement of the armature, and a series coil having an armature for exerting a force on the vibratory armature in opposition to the spring when the load reaches a predetermined value.

60 4. The combination with a dynamo electric machine having a field winding, of a regulator for regulating the ampere turns of the field winding, said regulator having a vibrating armature, one or more voltage coils for vibrating the same, a spring for opposing the movement of the vibrator under

the influence of said coil or coils, a series coil responsive when substantially a predetermined load is reached for exerting a force on the armature opposite to that exerted by the spring, and means whereby the series coil is ineffective below said load.

5. The combination with a dynamo electric machine having a field winding, of a regulator for varying the ampere turns of the field winding, said regulator comprising a shunt magnet having a vibratory armature and one or more voltage coils for vibrating the same and responsive to changes in voltage, and a series magnet which when substantially a predetermined load is reached exerts a force on the vibratory armature to assist the voltage coil or coils, said series magnet having a series coil and a core separate from the shunt magnet.

10 6. In combination with a dynamo electric machine having a field winding, of a regulator for varying the ampere turns of the field winding, said regulator comprising a vibratory armature biased toward closed position by a spring, one or more voltage coils responsive to changes of voltage for vibrating the armature, and a series magnet having an armature adapted when the armature is attracted at substantially a predetermined load to exert a force on the vibratory armature in opposition to the spring.

15 In testimony whereof, I hereunto affix my signature.

BENNETT M. LEECE.
